UNITED STATES PATENT OFFICE.

LOUIS S. CANNON, OF ROSEMARY, NORTH CAROLINA.

JACQUARD-CARD WIRE.

1,072,572.

Specification of Letters Patent.

Patented Sept. 9, 1913.

Application filed May 24, 1913. Serial No. 769,776.

To all whom it may concern:

Be it known that I, LOUIS S. CANNON, a citizen of the United States, residing at Rosemary, in the county of Halifax and 5 State of North Carolina, have invented certain new and useful Improvements in Jacquard-Card Wires, of which the following is a specification.

My present invention pertains to card 10 wires designed more especially for use in conjunction with jacquard cards, the construction and advantages of which will be hereinafter set forth, reference being had to the annexed drawings, wherein:

15 Figure 1 is a plan view, showing a series of interlaced cards, with two of the card-wires applied thereto; Fig. 2 a transverse sectional view taken on the line *a—a* of Fig. 1, the parts being slightly enlarged; and 20 Fig. 3 a perspective view of a wire.

The main object of the invention is to produce a simple and yet efficient form of 25 wire, which may be readily attached to the card-lacings without the employment of strings, staples or the like.

A further object of the invention is to produce ends upon the wires which will afford sufficient support for the cards and yet at the same time slide readily upon the 30 card-cradle.

A still further object of the invention is to provide a wire with an end and intermediate lacing-engaging loop and the other end thereof with a third loop which opens in 35 a direction opposite to that of the other two loops, whereby a lacing may be readily secured by first engaging the end and intermediate loops which open in the same direction and then engaging the oppositely-extending end loop which, of course, will 40 necessitate the movement of only one of the lacings to a slight extent.

Referring to the drawings, it is to be 45 noted that I have shown two wires in close relationship, but as will be understood by those skilled in the art such positioning does not take place in actual practice, the same being merely shown in this manner for the purpose of illustration.

50 The cards are indicated by 1, and the lacings by 2, 3 and 4, respectively, the first and last being the outer lacings, and 3 being the intermediate one.

55 The wire is formed from a single piece, having its ends bent back upon the body of the wire and twisted, the free end being

spaced away from the body of the wire to a slight extent, as will be clearly seen upon reference to the drawings. This construction produces an end 5, with a twisted portion 6; the free end, which is designated by 7, acting in conjunction with the adjacent body portion of the wire, forms a loop for the reception of the lacings, as for instance, 60 2. The opposite end of the wire is manipulated in the same manner, and forms a second loop, the free end of the wire being designated by 7^a. Said end, as will be seen upon reference to the drawings, extends in a direction opposite to the end 7. In other 65 words, this loop is designed to engage the outer row of lacings 4. As will be seen upon reference to the drawings, these loops open in opposite directions and are spaced apart a distance equal to the distance between the lacings 2 and 4. 70

The wire intermediate the end loops, as they may be termed, is provided with a central loop formed by bending the wire into a substantially S shape, with the upper members of the S brought into contact with each other. A plane which would pass through these various members of the central loop, designated by 8, will also pass through the members of the end loops, and would be at 85 right angles to a plane passing through the component members of the ends 5 and 5^a of the wires.

By bringing the component members of the various loops into a common plane, no 90 disarrangement of the lacings takes place, and the spacing between the edges of the cards is in no wise interfered with. It will also be noted that the twisted portion 6 of the wire lies within the limits of the card, 95 so that only the flattened portion 5 projects, and there is no tendency of the wire to roll and to become misplaced as it travels through the cradle. It will furthermore be noted that the body of the wire and the inwardly-projecting end 7 or 7^a adjacent thereto diverge equally from the twisted portion 6, as will be best seen upon reference to Fig. 3. This throws the end sections 5 and 5^a in alignment with the card lacings. 100 105

Having thus described my invention, what I claim is:

1. A card-wire having opposite end loops opening toward each other, and a central loop, the component members of 110 said loops all lying in a common plane.

2. A card-wire formed of a single piece

of wire bent to shape, each end thereof being bent back upon itself and producing a flattened portion, a twisted portion adjacent thereto and a free member which, 5 with the body of the wire, forms a loop; and an intermediate loop formed by bending the wire back upon itself into S-shape, one portion of the S being flattened.

3. A card-wire formed of a single piece 10 of wire bent to shape, each end thereof being bent back upon itself and twisted, the projecting end of the completed wire being composed of two sections which lie in close contact with each other; a twisted 15 portion adjacent thereto; a loop formed by the original end of the wire and the adjacent body of the wire; and an intermediate loop formed by bending the wire back and forth upon itself, the parts of the loop lying 20 in a common plane, which plane stands at right angles to the plane which passes through the members of the outwardly-extending ends of the completed wire.

4. A card-wire having flattened ends, and 25 lacing-engaging loops.

5. A card-wire having flattened ends, and

lacing engaging loops adjacent thereto, the loops opening in opposite directions.

6. A card-wire having flattened ends formed by doubling the ends of the wire upon themselves, the wire being twisted adjacent said ends and likewise having the extreme free ends forming loops with the adjacent portions of the body of the wire. 30

7. A card-wire having flattened ends, a 35 loop adjacent each end, and a central loop, the component members of said loops all lying in a common plane, which is at right angles to the flat sides of the ends.

8. A card-wire having flattened ends, 40 and a plurality of loops, the component members of said loops all lying in a common plane which is at right angles to the flat sides of the ends.

In testimony whereof I have signed my 45 name to this specification in the presence of two subscribing witnesses.

LOUIS S. CANNON.
